UNITED STATES PATENT OFFICE.

AMBROUS ADAM BROOKS AND ANDREW JACKSON BROOKS, OF MACOMB,
TEXAS.

PITMAN-ROD.

SPECIFICATION forming part of Letters Patent No. 317,919, dated May 12, 1885.

Application filed March 24, 1885. (No model.)

To all whom it may concern:

Be it known that we, AMBROUS A. BROOKS and ANDREW J. BROOKS, of Macomb, in the county of Grayson and State of Texas, have 5 invented certain new and useful Improvements in Pitman - Rods; and we do hereby declare the following to be a full, clear, and exact description of the invention, such as will enable others skilled in the art to which it pertains 10 to make and use it, reference being had to the accompanying drawings, which form part of this specification.

Our invention relates to an improvement in pitman-rods; and it consists in the combination 15 of the fly-wheel, made heaviest upon one side, with the wrist-pin, connecting-rod, and the part which is to be attached to the reaper or mower knife, as will be more fully described hereinafter.

20 Figure 1 is a vertical section taken through the wheel and pin. Fig. 2 is a side elevation of our invention complete, partly in section. Fig. 3 is a plan view.

A represents the fly-wheel, which is made 25 heavier at B than at any other portion. This heavy portion is made just opposite the point at which the wrist-pin C is attached to the wheel, for the purpose of balancing the wheel, and causing it to run more evenly than it 30 would do if the wheel were not made heavier on one side. The wrist-pin C is made square where it passes through the wheel, and a nut is applied to that end which projects through the wheel, for the purpose of securing it in position. This wrist-pin is made round where 35 it passes through the boxing upon the end of the pitman, and has the head D formed upon the end which comes next to the boxing, for the purpose of securing it in place. The two 40 parts of the boxing are held in contact with the wrist-pin by means of a strap, E, and the two keys G H, which secure the strap to the end of the connecting-rod. The two keys pass

through the two slotted ends of the strap and a slot in the end of the connecting-rod, and 45 these keys are held in any desired position by means of set-screws I, which are passed through the side of the connecting-rod, and made to bear against the two keys, as shown. Owing to the constant shaking of the different parts 50 these keys, when not locked in place, are liable to drop out, and thus disable the machine. Where set-screws are used, as here shown, these parts cannot become displaced. To the opposite end of the connecting-rod is attached 55 casting L, which has the flanges N formed upon opposite edges, and through which flanges is passed the coupling-pin N'. This end of the connecting-rod is also provided with a slotted strap, which secures the parts of the boxing 60 directly to the end of the connecting-rod by means of keys, which are also held in place by means of set-screws.

Over the top of the wrist-pin and the connecting-pin just described are formed openings in the straps, and in which openings oil-cups are fastened, so as to keep the parts constantly lubricated.

The flanged casting is to be secured to the knife of the reaper or mower in any suitable 70 manner.

Having thus described our invention, we claim—

The combination of the fly-wheel, made heaviest on one side, the wrist-pin, the boxing, 75 the slotted strap, the connecting-rod slotted at each end, the keys, and the set-screws for holding the keys in position, substantially as set forth.

In testimony whereof we affix our signatures in presence of two witnesses.

AMBROUS ADAM BROOKS.

ANDREW JACKSON BROOKS.

Witnesses:

JOSEPH KINCAID JAMISON,
ALBERT CHANEY.
